UNITED STATES PATENT OFFICE.

JOHN RUTHERFORD, OF SAN FRANCISCO, CALIFORNIA.

GRINDING AND PULVERIZING APPARATUS.

SPECIFICATION forming part of Letters Patent No. 224,357, dated February 10, 1880.

Application filed May 1, 1879.

To all whom it may concern:

Be it known that I, JOHN RUTHERFORD, of the city and county of San Francisco, State of California, have invented an Improved Pulverizing-Barrel; and I do hereby declare the following to be a full, clear, and exact description thereof, reference being had to the accompanying drawings.

My invention has reference to that class of rotary-barrel pulverizers in which ores and other substances are reduced to a powder or dust by means of balls, weights, or rollers placed loosely inside of the barrel with the ore, so that when the barrel is rotated the action of the balls or weights upon the ore will crush and grind it to a fine dust or powder.

My invention consists, first, in a novel arrangement for returning coarse particles from the periphery of the barrel to the center for recrushing, and for discharging to the outside of the barrel that portion which has been sufficiently pulverized; and, secondly, to an arrangement for supporting and driving the barrel, by which I apply the driving-power more economically, all as hereinafter more fully described.

Referring to the accompanying drawings, Figure 1 is an elevation and section of my improved pulverizing-barrel and frame. Fig. 2 shows a side view of the same. Fig. 3 is an elevation, showing the disposition of radial arms on the head of the barrel; and Fig. 4 is a lateral section of the barrel.

A is a large barrel, the heads H H' of which are made larger in diameter than the body or cylinder of the barrel. The periphery of each of these heads is formed with a tread and a flange similar to the periphery of a car-wheel, so that they will bear upon supporting-rollers, as hereinafter more fully described. The interior of this barrel I construct with two concentric crushing-floors, B C, one of which is nearer the axis of the barrel than the other, so that a considerable space is left between the two floors. Each floor is composed of a series of ribs or staves placed parallel with each other, and a narrow space is left between each two staves for the crushed ore to pass through. Each stave is made thicker on one edge than on the other, so that the floors are uneven or ribbed, by which means the balls, weights, or

rollers will be kept continually changing their position as the floors rotate under them.

The spaces between the staves which form the inner floor are wider than the spaces between the staves of the outer floor.

The outside shell or cylinder, D, of the barrel is made slightly conical or tapering from one head of the barrel to the other, for the purpose of directing all the crushed ore which passes through the screen E to one end of the barrel.

The screen E is arranged between the outside shell and the outer crushing-floor, B. This screen is also conical, and it is placed parallel with the outside shell, so that it will carry the particles of ore that are too large to pass through its meshes to the same end of the barrel that the fine particles which pass through it are directed by the outside shell.

The feed-opening G is made through the center of the head H, to which the small end of the conical shell D is secured, so that the ore is fed upon the inner floor, C. After it has been pulverized to a sufficient fineness upon this floor by the balls, weights, or rollers to permit it to pass through the spaces between the slats or staves, it passes through to the outer or second floor, where it is further subjected to the action of the balls, weights, or rollers, and further reduced, so that it will pass through the spaces in this floor and be caught upon the screen E.

The conical form of the screen causes the particles that are too large to pass through the meshes of the screen to travel toward the head H' of the barrel, while the finer particles which pass through the screen are caught upon the outer shell, D, and are also carried toward the head H'.

A disk, I, is secured to the outer edge of the flange of the head H', so as to cover the entire space inside of the flange and form a narrow chamber between the outer face of the head and the disk. In the center of this disk is an opening, from which a discharge tube or spout, J, projects. The space between this disk and the face of the head H', I divide into two or more separate chambers by means of radial ribs or partitions K K. In the present instance I have represented this space as being divided into six compartments, because

I shall usually employ that number. Every alternate compartment *l*, I make tight at the end, near the center of the head, while the other compartments, *l'*, are open, and connect with the discharge tube or spout *J*. I then make an opening, *m*, through the head *H'*, between the outer floor, *B*, and the screen *E*, so as to connect the space between them with the outer end of each compartment *l*, and 10 another opening, *n*, to connect the inner end of each compartment with the central space in the barrel, so that the large particles of ore, which are carried by the inclined screen against the head *H'* of the barrel, will pass 15 out into these closed compartments through the openings *m* and fall to their inner ends, where they will pass again through the openings *n* into the center of the barrel, to be again acted upon by the balls, weights, or rollers. 20 I also make openings *o* through the head *H'*, between the screen and outer shell, *D*, so as to connect the space between the screen and shell with the compartments *l l'*, through which the finely-pulverized ore that passes through 25 the screen will be conducted into the compartments *l'*, that connect with the discharge-spout *J*. By this arrangement all of the particles that are too large to pass through the screen are automatically carried back and passed again 30 through the pulverizer, while the fine particles are discharged through the spout *J* to the outside of the barrel.

As before stated, the heads of the barrel are provided with a flange and tread similar to 35 that of a car-wheel, and the tread rests upon rollers. These rollers, *p p*, are mounted in the ends of a semicircular supporting-frame, *Q*, so that the barrel rests upon a pair of rollers on each side of its center. The bearings of 40 these rollers are elongated, and the journals are adjustable horizontally by means of a set-screw, *r*, so that they can be set to or from the bearing-edge of the heads, for the purpose hereinafter specified.

45 I drive the barrel by means of friction-rollers *s s* on the driving-shaft *t*. This shaft extends across the semicircular frame *Q*, directly underneath the barrel, and is supported in adjustable boxes *u*. These boxes can be adjusted concentrically with the barrel in either

direction by means of set-screws *v v*, as shown. This arrangement is of the utmost importance, as it enables me to adjust the driving-rollers so that they will counterbalance the weight of the balls, weights, or rollers in the 55 barrel, as well as the charge of ore.

By means of the set-screws *r*, I can set the outside supporting-rollers, *p*, so as to throw more or less of the weight of the barrel on the driving-roller, and by adjusting the driving-shaft I can set the driving-rollers so that they will be directly under the load, and thus drive the barrel with a less amount of power than if the shaft were stationary. This arrangement can also be applied to amalgamating and other 65 trundling barrels.

By these improvements I have greatly increased the crushing capacity of the pulverizing-barrel and reduced the power required to drive it. I can employ as many grinding-floors as the diameter of the barrel will permit, and each additional floor will give the barrel additional pulverizing capacity. 70

Having thus described my invention, what I claim, and desire to secure by Letters Pat- 75 ent, is—

1. In a pulverizing-barrel, the combination, with the inner inclined sieve, *E*, one or more concentric floors, *B C*, and the crushing-balls, of the inclined cylinder *D*, with its enlarged 80 head, provided with ribs or partitions *K K* and a disk, *I*, which form tapering radial chambers *l l'* and passages *m n o*, the passages *m* connecting the space inside of the sieve with the chamber *l*, communicating, through the 85 passages *n*, with the central chamber of cylinder *D*, and passages *o* connecting the space exterior to the sieve with the chamber *l'*, communicating with the discharge-tube *J*, as set forth. 90

2. In combination with a pulverizing-barrel, *A*, the adjustable supporting-rolls *p p* and the adjustable driving-rolls *s s*, substantially as and for the purpose described.

In witness whereof I have hereunto set my 95 hand and seal.

JOHN RUTHERFORD. [L. S.]
